UNITED STATES PATENT OFFICE

JOHN ROGER OLIVER, OF MEDFIELD, MASSACHUSETTS, ASSIGNOR TO REECE SHOE MACHINERY COMPANY, OF BOSTON, MASSACHUSETTS, A CORPORATION OF MAINE

WELT-SEWING MACHINE

Application filed June 28, 1927. Serial No. 202,039.

This invention relates to welt sewing machines, and more especially to sewing machines known as welt-and-turn machines. An example of such machine is the Reece 5 weler in which the shoe insole is stitched to the lip of the upper and to the welt strip, exemplified by Patents 1,288,366 of December 17, 1918 and 1,361,952 of December 14, 1920. An appropriate stopping and starting mechanism for such machines is shown in my Patent 1,532,634 of April 7, 1925. My prior application Serial No. 21,544 filed April 8, 1925 10 discloses improved mechanism for the feeding, guiding and applying of the welt strip, certain features of which are employed with the present invention. I have heretofore devised certain mechanisms for severing the welt strip after the stitching of a seam and the stoppage of the machine and have applied 15 for patents thereon applications Serial Nos. 65,014 filed October 26, 1925 and 68,191 filed November 10, 1925. These prior patents and applications may be referred to for various details not herein fully shown or described. 20 The novel features of the present invention however are applicable to other makes and types of welt sewing machines useful in stitching welts or strips to various materials. 25 The general object of the present invention is to afford a simple, convenient and effective mechanism for the handling of the welt in such sewing machines. A particular object is to improve the mode of trimming off or severing the welt strip after the termination of 30 a seam, this being done, under the principles of prior application 68,191, in a manner to leave a projecting length of welt for the commencement of a new seam. The severing device is preferably controlled by a lever 35 thrown manually or by a blow from the shoe or work at the will of the workman, after the machine has been stopped, and one feature of the present invention is the provision of a safety device preventing the premature actuation of the severing mechanism. Another 40 feature of the present invention is the employment of a welt holding means or pawl, normally inoperative, but brought into operation at a proper time to hold the severed welt 45 end in its advanced position and prevent ac-

cidental movement thereof. Other and further advantageous features of the present invention will be pointed out in the hereinafter following description of an illustrative embodiment thereof or will be understood to 50 those conversant with the subject.

To the attainment of the above recited objects and advantages the present invention consists in the novel welt sewing machine, the novel welt handling mechanism, and the 55 novel features of combination, arrangement, operation, structure and detail herein illustrated or described.

In the accompanying drawings Fig. 1 is a 60 right elevation of a sufficient part of a welt sewing machine to illustrate the principles of the present invention, this view corresponding generally with Fig. 1 of said application 68,191.

Fig. 2 is a left elevation corresponding generally with Fig. 2 of said application 68,191. 65 Fig. 3 is a right elevation of a detached part, namely the welt severing blade and its carrying segment.

Fig. 4 is a plan view of certain parts of the 70 mechanism looking downward in the slanting direction indicated by the arrow 4 in Fig. 2, other parts of the mechanism being omitted for clearness of illustration.

Fig. 5 is a fore and aft section view taken 75 on the line 5—5 of Fig. 4, looking from the left.

Fig. 6 is a front view of certain parts of the mechanism shown in Figs. 1—5, looking 80 rearwardly in the slanting direction indicated by the arrow 6 in Fig. 2.

Fig. 7 is a front elevation of certain parts. 85 Fig. 8 is a left elevation of certain details.

Fig. 9 is a plan view taken partly in section on the line 9—9 of Fig. 8.

Referring in detail to the drawings the 90 inverted shoe, which is not shown, will be understood as being held in place to the front of and below the welt guide, and with the welt strip W, the shoe upper, and the sole lip advancing leftward in the path of the curved barbed needle C which may be 95 slidable in the usual oscillating guide c. The welt strip, before meeting the shoe, is guided by the welt guide along a path indicated at w, 100

The drawings show an upright fore-and-aft frame wall 11 which may be the left hand frame wall of the machine, and spaced to the right of this is seen another frame wall or fixed bracket 12. The main or operating shaft 13 may have its bearings in the frame walls, and this shaft may be a crank shaft which operates the needle, looper and other stitching instruments by means of links, 5 levers, etc., on the principles of said prior patents. These parts are not herein shown. Part of the mechanism hereof is mounted at the left or outer side of the frame wall 11, while various other parts are mounted at the 10 inner or right side of the wall, or between the two frame walls. For the purpose of mounting certain parts the left frame wall is shown as having formed or attached to its inner or right side a fixed irregular bracket 15 or casting 17 having various extensions as indicated by the reference number 17 applied thereto. The needle C may oscillate about an axle 18 in the usual manner. The work may be held against the welt guide and the 20 usual type of work rest, and may be advanced between stitches by the usual feed mechanism, while the welt W is laid against the shoe and stitched in place as more fully explained in the prior patents and applications. 25 The parts thus far described may be substantially preexisting parts of the welt stitching machine, although modified to accommodate the present invention.

The present invention operates on the following plan basically similar to said application 68,191. A welt severing blade is arranged to be thrown quickly forward and retracted when the welt is to be cut, this blade operating with a shearing action in conjunction with a part or member through which the welt advances. These parts are manipulated so as to sever the welt, not adjacent to the stitching point, or the plane of the needle, but at a point substantially advanced therebeyond, or well to the left of the stitching point, so that when severed there will remain a projecting welt, for example 1" in length, facilitating the starting of the sewing of the welt to the next piece of work or shoe. The particular construction shown is one in which the severing knife as it swings forwardly toward the welt is at the same time shifted toward the left, thus receiving a diagonal motion and bringing it to the desired advanced severing position. In connection with this action the welt guiding member, which may be a part of the welt guide, or any part looping or surrounding the welt, will preferably be moved leftward 45 along the direction of feed, thus giving support to the welt during the severing action and cooperating with the blade to shear the strip. In other words the blade and the loop member move leftward in unison, while the 50 blade moves relatively forward to cut the

welt. The operator may therefore, after the completion of a seam and the stoppage of the machine, pull the shoe and welt bodily leftward to the extent of two or three inches if that amount of loose welt is desired to be left at the end of the seam and then bring about the severing action, for example at one inch to the left of the sewing plane, thus leaving the desired free welt end on the completed work, and as well a projecting free end in the machine for starting the next shoe. If the severing devices should be put into action without manually pulling the shoe and welt to the left, the loop member, surrounding the welt, will bear forwardly and compel the shoe and welt to advance sufficiently to insure that the severing will be at an unattached part of the welt and that the blade will not injure the work already completed.

The welt guide 20 is a member swingable forward toward the work and rearward from the work and with a recess or surface along which the welt is guided to the work. The guide is an irregularly shaped casting supported on a pair of swinging arms 22 which turn on an axle 23 extending between a portion of the casting 17 and the wall 12.

As in application 68,191 the welt passes through the main welt guide 20 and thence through a separate guiding part or loop 24 located directly to the left of the welt guide and capable of leftward shifting movement at the time of severing, as already explained. The shiftable guide part or loop member is herein shown as having a rigid extension piece 25 spaced to the left and forming a recess in which the cutter can move. This may have a slotted adjustment, so that a curved extension 25a may be adjusted as a gib in the welt passage 26 in the loop member 24 for welts of different width.

The shiftable welt loop member 24 is shown mounted at the lower end of a supporting shank 27 having a circular head 28 by which it is swingingly mounted in a member to be later described. This permits the separate guide section 24 to partake of the swinging movements of the main guide 20 during the stitching operations, the shifting guide section normally lying against the main guide, and being held in alinement thereto at all times, for example by a longitudinal alining pin 29 forming a rightward extension of the shifting guide section and passing through an aperture in the main guide, and projecting beyond the latter at the right, where it is notched as seen in Figs. 1 and 7 for certain purposes.

The severing knife 30 consists of a flat blade movable in the groove between the shifting guide part 24 and its spaced extension 25. The knife is shown separately in Fig. 3 and is attached to a curved shank 31 carrying a toothed rack 32 engaged by a

pinion 33 which is elongated to permit right and left shifting movements of the cutting blade. Upon rotation of the pinion as will be later described the cutter blade is caused 5 to advance, cut the welt, and retract to normal position.

The curved shank 31 of the cutter and the similar shank 27 of the guide section 24 are accommodated in the arc shaped recess of a 10 guide member or block 35 which not only guides the two shanks and keeps them in proper registered position, but is employed to give the bodily leftward and return shifting movements of the cutter and the guide 15 loop section 24. The shifting guide 35 is mounted on or formed with a guiding bar 36 extending to the right, and a similar bar 37 extending to the left and passing through the frame wall 11, these two bars being guided 20 respectively in a portion of the casting 17 and in the frame wall. The left and right movements of the guide block and connected parts may be effected through the carrying bar 37. For this purpose the bar is shown 25 provided with lateral pins 38 engaging in the lower slotted end of a lever 39 at the outer or left side of the wall 11, this lever being fulcrumed at an upper point 40 and being swung right and left by a link 41 extending from 30 an upwardly and downwardly sliding bar 45 to be further described. When the bar 45 descends and rises this will throw the guide block 35 to the left for the cutting movement and return to the right or normal position. 35

The connections for operating the cutter blade may now be described. The pinion 33 which operates the curved rack 32 of the cutter shank is mounted on a shaft 42 which 40 extends leftward through the frame wall 11 and at its exterior end carries a pinion 43 engaged by the teeth 44 of a rack bar 45 arranged to slide downwardly and upwardly guided by a lower guide 46 and at its upper 45 end a guiding roll 47. The bar 45 has pivoted to it the links 41 already referred to for throwing the lever 39 and connected parts. At its upper end the rack bar 45 is formed with an extension 48 through which its down and up movements are effected. There is 50 herein shown mechanism generally similar to application 68,191 for effecting these movements. A toggle device is employed comprising a lower link 50 pivoted to the extension 48 and an upper link 51 centrally pivoted to the lower link by a pin 52, the upper link having an upper pin 53 engaging in a slot 54 having a notch 55 at its lower end in which the pin rests during the rearward or operative movement of the toggle. A spring 56 normally holds the toggles in their lowered position shown, with the pin 53 engaging the notch 55. The toggle is shown operated by 55 a rod 58 extending forwardly from the pin 52, and this rod having a rear head 59 by

which the parts can be reset. The rod carries a flange 60 in front of the toggles to confine the operating spring, and it also has a tapered front end 61 with a latch receiving notch 62 to the rear of the taper. The preferred operation of the cutter blade is by the stored tension of a spring 63 which is shown surrounding the rod 58 and pressing rearwardly on the flange 60 and the toggles. The front end of the rod may be guided by a fixed bearing 65 which may be supplemented by a sleeve 66 as in application 68,191. The operation of the spring, when released, is to throw the toggles from the normal position shown in Fig. 2 through their straightened position and beyond to a rearward position, thus throwing the bar 45 downwardly and upwardly. The subsequent resetting may be effected after the restarting of the machine, namely by an oscillating lever 67 actuated by a link 68 from the main shaft 13 as in application 68,191, the resetting lever forcing the toggle rod forwardly to normal position where it becomes latched. 70

Normally, and during stitching operations, the toggle mechanism is latched in its forward position as shown, namely by a latch or finger 70 engaging in the notch 62 near the forward end of the rod 58. The latch is in the form of a swinging finger mounted on a fore-and-aft shank 71 located somewhat to the left of the toggle rod. When the latch is thrown down this releases the rod and brings about the leftward and rightward shifting movements of the guide block 35 carrying the guide loop 24 and the knife 30, as well as the cutting and return movements of the knife itself. The mounting of the latch may be as follows. Its shank or carrying shaft 71 is shown rotating in a front fixed bearing 72 and a rear bearing 73, see Figs. 2, 4 and 5. To the rear of the bearing 72 the shank 71 has a collar 74 clamped upon it, and a spring 75 which surrounds the bearing and the collar is so connected to them as to rotate the shank and lift the latch into latching position. Also, it is under compression and holds the parts in proper endwise relation. The collar 74 is formed with a tooth 76 engaging with loose play in the recess 77 of a sleeve member 78 in which the shank 71 turns, within bearing 73. The sleeve 78 has a spoke-like extension 79 constituting an inclined lever extending to the left and downwardly in a convenient position to be contacted or knocked up by the work, or without letting go of the work, and lifted so as to throw down the latch and bring about the severing operation. A spring 80 is shown connected to the bearing 73 and the sleeve 78 and tending to throw downwardly the severing control lever 79. The sleeve 78 is formed into a rearwardly extending shank 81 which has clamped to it a collar 82 from which extends an upstanding finger 83 taking part in 80

the welt pawl applying action to be described. The play between the lever 79 and the latch, namely in the looseness between tooth 76 and notch 77, permits enough slack so that the 5 welt holding pawl will not be affected or moved when the latch 70 snaps back into place.

The welt guide 20 is continuously pressed forward toward the work, partly through resilient connections as illustrated in application 21,544, but is herein locked forward at 10 certain parts of each stitch cycle by a wedging means. The rod 84 on Fig. 1 is representative of the connections pressing forwardly on the welt guide, and corresponds with the rod 78 in said application, being pivotally connected to a rear extension of the welt guide. Extending downwardly and forwardly from the same pivot is shown a locking finger 85 normally engaging in the 15 notch of the alining pin 29 already referred to, as indicated in Figs. 1 and 7. The tail 85^a of the finger 85 stands above the foot of a fixed stop bracket 86, the arrangement being such that when the shoe is in the machine, and the welt guide thereby held in its rearward position as shown, the lock finger 85 engages and locks the alining pin 29, whereas, after the stitching, and the removal of the 20 work, if the guide is allowed to swing clear forward the tail 85^a will strike the stop 86 and cause relative swinging of the lock finger 85 and the release of the alining rod. This 25 arrangement prevents premature operation of the severing mechanism for the reason that the alining pin 29 is a part of the shifting guide loop member 24, which latter is thus prevented from being shifted leftward, this 30 in turn holding the entire train of parts of the severing mechanism, even to the extent that the link 41 holds the rack bar 45 against being moved downwardly by the toggle devices. The operator therefore is unable to 35 effect the severing operation until after the completion of the stitching and the removal of the work.

In connection with these safety devices there is shown a guard hook 88 pivoted at the lower rear part of the welt guide, this 40 extending rearwardly and being there pivoted to an inclined slide 87 sliding in the casting 17, with a stop pin 87^a arranged to strike the casting and so determine the most forward position of the welt and guide. The 45 guard hook 88 is adapted to engage upon a guard 89 having a part projecting upwardly in front of the hook. These cooperating parts normally prevent the full forward movement of the welt guide in a positive manner. The guard 89 is mounted on a 50 shank 90 fulcrumed at 91 in the block 17 and it carries an operating pin 92 mounted on an extension and engaged by the slotted end of a lever arm 93 fulcrumed at 94 to 55 the frame wall and having a rearward ex-

tension 95 normally pulled down by a spring 96 which thereby holds the guard in its operative position. After the completion of a seam, and the letting up of the pedal to stop the machine, these parts may be shifted to release the welt guide. Thus a sliding pin 97 is shown which may be arranged to rise upon the stoppage of the machine, for example by direct connection with the pedal, and being so located as to throw upwardly the lever arm 95 and thereby pull down the guard 89, releasing the welt guide to swing full forward, this in turn effecting the throw of the lock finger 85 and the release of the severing mechanism as already described.

An advantageous feature of operation of these described parts is that the welt guide must necessarily move completely forwardly, with a snapping action, when released by the guard, before the actual severing operation takes place. It will be understood that the needle oscillates forwardly and rearwardly in the recess or groove in the shiftable welt guide loop 24, 25, and that this loop member is in alinement with the main welt guide, but partakes of a sharp leftward movement at the time of severing. With the welt guide and the loop member in retracted position the leftward movement will be likely to strike the point of the retracted needle and break it. The necessary quick forward shift of the welt guiding parts however before the severing movements insures these parts clearing the needle.

Another feature hereof consists of a welt locking device illustrated as a pawl 100 adapted to be brought into action upon the welt to prevent reverse movement after severing. The parts which have moved leftward during the severing move immediately back to their normal position and this tends to push the welt back instead of leaving the extending welt end as desired. With this invention connections are arranged whereby the initiation of the severing action causes the pawl 100 to be pressed upon the welt strip and thus hold it advanced. There are herein shown connections for this purpose which are accommodated without conflict in this very congested machine. The welt pawl 100 is shown mounted movably on the welt guide 20 in a position to overlie the welt strip passing therethrough, and at its upper side the pawl is formed with a constant lug 101. For depressing this lug to apply the pawl to the welt, as best seen in Fig. 6, there is shown a lever arm 102 mounted on a hub 103 loose on the axle 23. The depresser arm 102 is thrown downwardly by turning the hub by means of an upwardly extending arm 104 which is thrown rearwardly for the purpose. A lever arm 105 is arranged to press rearwardly by contact against the arm 104, the arm 105 is mounted on a hub which also carries an arm 107 extending upwardly and to the rear where

it is formed with a head 108 accommodated in a recess in the frame plate or bracket 12. A push bar or link 109 is shown mounted loosely in the two frame walls and contacting at its right and left ends respectively, the head 108 and the upstanding finger 83 rigidly connected with the severing control lever 79 as already described. By this arrangement when the control lever 79 is knocked upwardly to cause the severing action the finger 83 is thrown to the right and thus operates the rod 109 and the connected train of mechanism to press the pawl 100 down upon the welt *w* and prevent its accidental retraction.

It may be advisable to adjust the extreme right movement or return position of the welt guide loop member 24, the cutter blade 30 and the guide block 35 carrying them, following each cutting operation, so as to true them up in relation to the parts which do not reciprocate with them. Such adjustment may be effected as follows. At the left side of the frame plate 11 is shown a block 111 adjustable vertically by loosening bolt 112. This block has a converging recess 113 adapted to receive and position the rounded rear end of the toggle rod 58 in its extreme rear movement. A change of position of the block will alter the position of the rack bar 45 and accomplish the desired adjustment. There may also be a suitable adjustment for the leftward extreme movement of the guide block and connected parts.

In place of the pawl and ratchet shown in application 21,544 for locking forward at one point in each stitch cycle the welt guide there may be used herein a wedge member serving a similar purpose but giving a finer adjustment.

There has thus been described a welt sewing machine embodying the principles and attaining the advantages of the present invention. Since many matters of combination, arrangement, operation, structure and detail may be variously modified without departing from the principles it is not intended to limit the invention to such matters except so far as set forth in the appended claims.

What is claimed is:

1. In a welt sewing machine welt guide means and welt severing means comprising a welt loop member shiftable forwardly in the direction of feed during severing, a welt cutting blade movable toward the welt and shiftable forwardly with said loop member, the loop member having a slot and the cutting blade being fitted to move in such slot in the loop member and to give a shearing action on the welt, operating mechanism for shifting forwardly said loop member and blade while operating the latter, whereby the welt will be severed substantially beyond the stitching point, and means operable after stitching to put the operating mechanism into action.

2. In a welt sewing machine welt guide means and welt severing means comprising

a welt loop member shiftable forwardly in the direction of feed during severing, a welt cutter movable toward the welt and shiftable forwardly with said loop member, operating mechanism for shifting forwardly said loop member and cutter while operating the latter, whereby the welt will be severed substantially beyond the stitching point, and means operable after stitching to put the operating mechanism into action, the operating mechanism comprising a sliding bar (45), resilient means moving the cutter and sliding the bar, a swinging lever (39) for shifting the loop member and cutter, and a link (41) between the bar and lever.

3. In a welt sewing machine welt guide means and welt severing means comprising a welt loop member shiftable forwardly in the direction of feed when severing, a welt cutter movable toward the welt and shiftable forwardly with said loop member, operating mechanism for shifting forwardly said loop member and cutter and actuating the latter to sever the welt substantially beyond the stitching point, means preventing the operation of the operating mechanism during stitching but allowing operation after the cessation of stitching, and manual means operable at will after stitching to put the operating mechanism into action.

4. In a welt sewing machine welt guide means and welt severing means comprising a welt loop member shiftable forwardly in the direction of feed during severing, a welt cutter movable toward the welt and shiftable forwardly with said loop member, operating mechanism for shifting forwardly said loop member and cutter while operating the latter, whereby the welt will be severed substantially beyond the stitching point, including spring means for operating the cutter, a latch (70) restraining the spring, a spring pressing the latch, a knock lever having a loose connection with the latch for throwing it, and a spring pressing the lever.

5. In a welt sewing machine welt severing means comprising a welt loop member shiftable forwardly during severing, a welt cutter movable toward the welt and shiftable forwardly with said loop member, operating mechanism for shifting forwardly said loop member and cutter while operating the latter, whereby the welt will be severed substantially beyond the stitching point, a control lever operable to put the operating mechanism into action, and means preventing the operation of said lever during stitching.

6. A welt sewing machine as in claim 5 and wherein the preventing means operates by locking the loop member against forward shifting.

7. In a welt sewing machine a main welt guide, welt severing means comprising a welt loop member adjacent to said guide but shiftable forwardly during severing, a pin alining

said guide and loop member, a welt cutter movable toward the welt and shiftable forwardly with said loop member, operating mechanism for shifting forwardly said loop member and cutter while operating the latter, whereby the welt will be severed substantially beyond the stitching point, and means for locking said pin to prevent operation during stitching.

8. In a welt sewing machine welt severing means comprising a welt guide member pressing transversely to the direction of feed during stitching and shiftable forwardly during severing, a welt cutter movable toward the welt and shiftable forwardly with said guide member, operating mechanism for shifting forwardly said guide member and cutter while operating the latter, whereby the welt will be severed substantially beyond the stitching point, a guard for said guide member preventing complete transverse movement during stitching, means releasing the same after the stitching, and means preventing the operation of the severing mechanism until after the guard releases the guide member.

9. In a welt sewing machine welt severing means comprising a welt loop member shiftable forwardly during severing, a welt cutter movable toward the welt and shiftable forwardly with said loop member, operating mechanism for shifting forwardly said loop member and cutter while operating the latter whereby the welt will be severed substantially beyond the stitching point, and for returning the same, and means preventing reverse movement of the welt after the severing action.

10. A welt sewing machine as in claim 9 and wherein the preventing means comprises a welt holder and means putting it into action at the time of severing the welt.

11. A welt sewing machine as in claim 9 and wherein the preventing means comprises a welt holder and means putting it into action at the time of severing the welt consisting in a lever system for putting pressure on the welt holder and a control lever or handle for operating the same, and means controlled by the same lever for causing the operation of the operating mechanism.

In testimony whereof, I have affixed my signature hereto.

JOHN ROGER OLIVER.
